[57] CLAIM

The ornamental design for a heater fan, as shown and described.

DESCRIPTION

FIG. 1 is a front perspective view of the heater fan of the present invention in a horizontal position;

FIG. 2 is a right side view in elevation of the heater fan of FIG. 1;

FIG. 3 is a left side view in elevation of the heater fan of FIG. 1;

FIG. 4 is a top plan view of the heater fan of FIG. 1;

FIG. 5 is a bottom plan view of the heater fan of FIG.

1;

FIG. 6 is a front view in elevation of the heater fan of FIG. 1;

FIG. 7 is a rear view in elevation of the heater fan of FIG. 1;

FIG. 8 is a second embodiment of the heater fan shown in FIG. 1 and showing a front view in elevation of the heater fan, said second embodiment being identical to that of FIGS. 1-7, except for the appearance of the added stability boot at its lower end; and,

FIG. 9 is a side view in elevation of the heater fan of FIG. 8.

FIG. 1

FIG. 2

FIG. 3

FIG. 4

FIG. 5

FIG. 6

FIG. 7

FIG. 8

FIG. 9
